HOLLOW-WALLED CARTON

William P. Frankenstein, Cincinnati, Ohio

Original application July 21, 1941, Serial No. 403,376. Divided and this application March 15, 1943, Serial No. 479,155

5 Claims. (Cl. 229—34)

1

This invention relates to improvements in cartons and particularly to improvements in cartons of the "knocked down" type.

This application is a division of copending application Serial No. 403,376 for Cartons filed July 21, 1941, now Patent No. 2,397,934.

In the past there has been provided hollow wall cartons such as disclosed in applicant's Reissue Patent No. 21,158, dated July 25, 1939, on which the present application is an improvement. It is frequently desirable to provide hollow wall cartons of a shallow type whereby articles originally shipped therein may be retained therein for display above the walls of said carton. In order to display the articles it is advantageous that the face of the article be inclined rearwardly from the observer and which position can be readily given to the articles by the formation of the carton or box displaying the same. The construction of the carton or box of the present invention fulfills these desirable qualities.

It is, therefore, the principal object of this invention to provide a carton or box of the knocked down variety having inclined inner supporting walls.

It is another object of this invention to provide a knocked down carton or box which can be readily erected for use as a shipping and displaying container and wherein the displayed articles are disposed at an inclination to the plane of support of the container.

Another object of this invention is the provision of a box or carton for accomplishing the foregoing objects which is formed of a single blank.

Other objects and advantages of the present invention should be readily apparent by reference to the following specification considered in conjunction with the accompanying drawings forming a part thereof and it is to be understood that any modification may be made in the exact structural details there shown and described, within the scope of the appended claims, without departing from or exceeding the spirit of the invention.

In the drawings:

Fig. 1 is a plan view of an extended blank partly broken away and partly folded from which the carton or box of this invention is formed.

Fig. 2 is a perspective view of a partly assembled carton utilizing the blank of Fig. 1.

Fig. 3 is a vertical sectional view taken substantially longitudinally centrally of an assembled carton of this invention.

Fig. 4 a plan view of the carton of Fig. 3 as seen on line 4—4 on said Fig. 3.

Throughout the several views of the drawings

2

similar reference characters are employed to denote the same or similar parts.

As was mentioned above this invention pertains to an improved carton of the knocked down type and particularly to a hollow wall carton wherein the inner wall member is inclined whereby articles may be mounted therein, while on display. In the following description references will be made to sides and ends, but it is to be understood that these terms are used merely for convenience in reference and not as limiting terms since the opposed longer sides are generally designated as sides while the shorter sides are frequently referred to as ends.

Specifically, the carton of this invention is formed from a blank indicated by the reference numeral 10 comprising a central panel 11 which forms the bottom of the carton. The sides of the bottom 11 are defined by fold or score lines 12, 13, 14 and 15 which are indicated in the drawings by dash lines; and it should be here noted that all dash lines on the drawings indicate fold or score lines. Extending from fold lines 12 and 13 are portions 16 and 17 which, in the carton illustrated in the drawings constitute the carton sides, while extending from the score lines 14 and 15 are, respectively, portions 18 and 19 which form the end walls.

Portions 16 and 17 are substantially identical in construction and it is deemed sufficient if but one of them be described in detail, accordingly, the portion 17 is provided with score or fold lines 20, 21, and 22 forming between them and the score lines 13 and outer edge of the portion 17, panels 23, 24, 25 and 26. The opposite ends of the panel 25 are respectively defined by score lines 27 and 28 which, respectively, hingedly connect thereto tucking flaps 29 and 30. Each of the flaps 29 and 30 has hingedly connected to it along its score or fold lines 31 and 32, which are in line with side portion score line 21, a spacer tab 33 and 34.

The end wall portions 18 and 19 are substantially identical in construction although the elements thereof are of different proportions which will be pointed out hereinafter while a description of the one of said portions is sufficient for the other. Accordingly, portion 19 is provided with a plurality of score or fold lines 35, 36 and 37 forming between them and score or fold line 15 and the end of the blank, panels 38, 39, 40 and 41. The opposite ends of the panel 40 are respectively, in part, defined by score or fold lines 42 and 43 which, respectively, hingedly connect to the ends of the said panel 40 spacer tabs 44 and 45. Further de-

fining the ends of the panel 40 are locking tabs 46 and 47.

A comparison of the panels of the end portions 19 and 18 will disclose that panel 41 of the end portion 18 is wider than the corresponding panel portion 41 of the end portion 19 while panel portion 39 of the end portion 18 is narrower than the corresponding panel portion 39 of the end portion 19 and the purpose for which will be pointed out subsequently.

The panel 25 of the side portions 16 and 17 are each provided near their ends and substantially adjacent the score or fold line 22 with inclined apertures 48 and 49 and the said panels are provided near one of their ends and adjacent the score or fold line 21 with a slit 50 thereby providing a tongue 51.

Each of the side panels 23 is connected at its opposite ends with the adjacent ends of the adjacent end panel 38 by a mechanism referred to in the trade as a "bellows corner." This bellows corner comprises a corner piece 52 connected by a score or fold line 53 to the side panel 23 and by a fold or score line 54 with the end panel 38. The corner piece 52 is further provided with a diagonal fold or score line 55.

The blank 10 is formed or cut from card or paper board material in one piece with each of the extensions 16 and 17 extended as side extension 17 is illustrated and with the fold or score lines, above specifically set forth formed at the time of cutting the blank. Adhesive 56 is also at this time applied to the under side of the side portions panels 26. Actually the said side portions panels 26 and 25 are first folded on the score lines 21 onto the side portions panels 24 and 23 before the said adhesive 56 is applied whereupon the said side portions panels 23, 24, 25 and 26 are folded about the score or fold line 13 onto the bottom panel 11 which is the arrangement illustrated for side portion 16 in Fig 1 and whereby the side portions panels 26 are adhesively secured to the bottom panel 11. It is in this condition that the cartons are shipped to the purchaser for subsequent use.

In order to assemble the carton, the sides 16 and 17 are raised from the illustrated folded position of side 16 to the upstanding position of the sides as illustrated in Fig 2 in which said carton sides are normal to the bottom panel. It will be noted that the sides are then provided with outer side wall members 23 normal to the bottom panel 11, top wall members 24 extending parallel with the bottom panel 11, inner sides wall members, formed by the panels 25, extending normal to the bottom panel 11 and with the outer panels 26 glued to the bottom panel 11. The tucking flaps 29 and 30 are then arranged across the bottom panel with their spacer flaps disposed parallel with the bottom.

The end portions or walls 18 and 19 are then assembled to complete the carton. Bellows corner pieces or portions 52 are folded inwardly along fold or score lines 53 and 54 causing each of them to fold on itself about the diagonal fold or score line 55. This operation causes the end extension 18 and 19 to be disposed normal to the bottom panel 11 with the panels 38 forming the outer end wall members. The remaining portion of each end wall extension is then folded as follows. The endmost panel 41 is bent along score line 37 to be at right angles to panel 40. Panel 39 is then bent about score line 35 at right angles to panel 38 to form end wall top member and is therefore parallel with the bottom panel 75

11. The panel 40 is then bent about score line 36 toward the outer end wall member 38 thereby forcing the lower end of said panel 40 and the panel 41 toward the outer end wall member and to lie parallel with and on the bottom panel 11. Due to the shortness of the panel 41 and when it contacts with the outer end wall member 38 it causes the inner end wall member 40 to lie at an angle to the bottom other than a right angle and actually to have its lower end beneath the top or end wall panel 39 as clearly illustrated at the right hand end of Fig 3. In other words the inner wall member is inclined upwardly and toward the center of the assembled carton and provides an angle of inclination which is the angle of inclination of the articles or goods to be displayed as illustrated in phantom lines at 57 in Fig 3.

With respect to the end wall portion 18 and having the opposite proportion in widths of the panels 39 and 41 from that of the corresponding panels of the end wall portion 19 the inner end wall inclines oppositely, namely, downwardly and toward the interior or center of the assembled carton as clearly illustrated at the left hand end of Fig. 3. In each instance, however, the inner wall member is inclined with respect to its outer wall member.

The end walls are retained against collapse first by side wall tucking flaps 29 and 30 and their spacer flaps 33 and 34 which underlie the end walls formed from end wall extensions and secondly by the tongues 51 which project toward one another from the tops of the inner walls members and around at the end wall panels 39 and 40 are folded. These parts are locked in the assembled positions by snapping the locking tabs 46 and 47, at the opposite ends of the end wall inner wall members 40, respectively, into the inclined apertures 48 and 49 of the side wall inner wall members 25.

In order to prevent the disarrangements of the goods or articles 57 upon removal, for example, of the first one, there is provided in the 45 carton means for preventing the lower end of successive articles from sliding forward due to their angular position. This means conveniently takes the form of a piece of so called "corrugated" board 58 which is provided transversely thereof with successive undulations 59. As is readily apparent from an inspection of Fig. 3 the lower 50 corner of articles 57 is disposed in the valley between successive ridges with the bottom of the article against the forward undulation and with the rear side of the last article in the carton 55 engaging the upper corner of the inner wall member of the hollow end wall. While the standard corrugated board actually fills the need for a means for maintaining the articles in the desired 60 position it will be understood that a stepped member may be substituted therefore.

It is believed that the foregoing clearly discloses the construction of a carton or box for the purpose originally set forth and provides a construction which will accomplish the desired 65 objects of this invention.

What is claimed is:

1. In a carton part of the class described comprising a base, side walls upstanding from said base, end walls from opposite ends of the base each formed from an extension subdivided by parallel score lines into portions adapted to form an outer wall member, an inner wall member and a top wall member, said inner and outer wall members being respectively of dissimilar dimen-

sion whereby the inner wall members are, respectively, disposed at an angle to the top wall members and carton base other than the angle of the outer wall members thereto, said inner wall members extending at angles to one another that are substantially supplementary, means projecting from said side walls engaged by an inner wall member to hold said inner wall member in position, and a corner tab hingedly connected to each end of each side wall adapted to be disposed across the base between the inner and outer end wall members.

2. In a carton of the class described comprising a base, extensions from each side of said base, two opposed extensions forming side walls and each extension being divided by score lines into panels with the panel adjacent the base and the third panel from the base of equal width, which panels, when in erected positions, form in each side wall an outer wall member, an inner wall member, a top wall member and a glue flap at the free end of one of the inner and outer wall members for securing the said wall member to the base a distance from the side thereof equal to the width of the top wall member whereby said inner and outer wall members are parallel throughout their height, the extensions from the remaining opposed sides of said base forming end walls and each extension divided by score lines into panels which, when in erected positions, form in each end wall an outer wall member, a top wall member, an inner wall member and a spacer member lying on the base between the lower ends of said inner and outer wall members and with said top wall member and spacer member of each end wall respectively of different widths whereby said inner and outer wall members are disposed at angles to the outer wall members and base, said inner wall members extending at angles to one another that are substantially supplementary, means projecting from said side walls inner wall members at a corresponding end thereof engaged by the adjacent end wall inner wall member to hold said inner wall member in position, and cooperating means on said side and end walls for holding said walls in erected operative positions.

3. In a carton of the class described comprising a base, extensions from each side of said base, two opposed extensions forming side walls and each extension being divided by score lines into panels with the panel adjacent the base and the third panel from the base of equal width which panels, when in erected positions, form in each side wall an outer wall member, an inner wall member, a top wall member and a glue flap at the free end of one of the inner and outer wall members for securing the said wall member to the base a distance from the side thereof equal to the width of the top wall member whereby said inner and outer wall members are parallel throughout their height, the extensions from the remaining opposed sides of said base forming end walls and each extension being divided by score lines into panels which when in erected positions form in its end wall an outer wall member, a top wall member, an inner wall member and a spacer member lying on the base between the lower ends of said inner and outer wall members and with said top wall members and spacer members of each extension or end wall of different widths whereby said inner wall members are disposed at an angle to the outer wall members and base, said spacer member of each end wall being of a

different width whereby the said end walls inner wall members extend at angles that are substantially supplementary to one another, and cooperating means on said side and end walls for holding said walls in erected positions, comprising apertures in the side walls inner wall members inclining at the angle of inclination of the end walls inner wall members, and locking flaps at the ends of the end walls inner wall members adapted for engagement with the inclined apertures.

4. In a carton of the class described comprising a base, extensions from each side of said base, two opposed extensions forming side walls and each extension being divided by score lines into panels with the panel adjacent the base and the third panel from the base of equal width which panels, when in erected positions, form in each side wall an outer wall member, an inner wall member, a top wall member and a glue flap at the free end of one of the inner and outer wall members for securing the said wall member to the base a distance from the side thereof equal to the width of the top wall member whereby said inner and outer wall members are parallel throughout their height, the extensions from the remaining opposed sides of said base forming end walls and each extension being divided by score lines into panels which when in erected positions form in its end wall an outer wall member, a top wall member, an inner wall member and a spacer member lying on the base between the lower ends of said inner and outer wall members and with said top wall members and spacer members of each extension or end wall of different widths whereby said inner wall members are disposed at an angle to the outer wall members and base, said spacer member of each end wall being of a different width whereby the said end walls inner wall members extend at angles that are substantially supplementary to one another, cooperating means on said side and end walls for holding said walls in erected positions, comprising apertures in the side walls inner wall members inclining at the angle of inclination of the end walls inner wall members, and locking flaps at the ends of the end walls inner wall members adapted for engagement with the inclined apertures, tucking flaps at the ends of said side walls inner wall members adapted to be disposed transversely of the base between the end walls inner and outer wall members, and spacer tabs on said tucking flaps adapted to underlie the end walls top wall members.

5. In a cartoon of the class described comprising a base, extensions from each side of said base, two opposed extensions forming side walls and each extension being divided by score lines into panels with the panel adjacent the base and the third panel from the base of equal width which panels, when in erected positions, form in each side wall an outer wall member, an inner wall member, a top wall member and a glue flap at the free end of one of the inner and outer wall members for securing the said wall member to the base a distance from the side thereof equal to the width of the top wall member whereby said inner and outer wall members are parallel throughout their height, the extensions from the remaining opposed sides of said base forming end walls and each extension being divided by score lines into panels which when in erected positions form in its end wall an outer wall member, a top wall member, an inner wall member and a spacer member lying on the base between the lower ends of said inner and outer wall mem-

bers and with said top wall members and spacer members of each extension or end wall of different widths whereby said inner wall members are disposed at an angle to the outer wall members and base, said spacer member of each end wall being of a different width whereby the said end walls inner wall members extend at angles that are substantially supplementary to one another, cooperating means on said side and end walls for holding said walls in erected positions, comprising apertures in the side walls inner wall members inclining at the angles of inclination of the end walls inner wall members, and locking flaps at the ends of the end walls inner wall members adapted for engagement with the inclined apertures, tucking flaps at the ends of said side walls inner wall members adapted to be disposed transversely of the base between the end walls inner and outer wall members, spacer tabs on said tucking flaps adapted to underlie the end walls top wall members, and a spacer flap at each end of the end walls inner wall members having the free ends thereof inclining in a direction substantially opposite to the direction of inclination

of the end wall inner wall members and engaging the end wall outer wall members for spacing the ends of said end walls inner and outer wall members from one another.
